UNITED STATES PATENT OFFICE.

CLYDE C. VOGLESONG, OF OAKLAND, CALIFORNIA, ASSIGNOR TO HIMSELF, AND PETER A. MCKENZIE, OF SAN FRANCISCO, CALIFORNIA, TRUSTEES.

FARE-BOX.

1,080,738.

Specification of Letters Patent.

Patented Dec. 9, 1913.

Application filed April 7, 1913. Serial No. 759,396.

To all whom it may concern:

Be it known that I, CLYDE C. VOGLESONG, a citizen of the United States, residing at Oakland, in the county of Alameda and State of California, have invented certain new and useful Improvements in Fare-Boxes; and I do hereby declare the following to be a full, clear, and exact description of the invention, such as will enable others skilled in the art to which it appertains to make and use the same.

My invention relates to new and useful improvements in fare boxes and more particularly to that class to be used in connection with "pay-as-you-enter" street cars and my object is to provide a receptacle into which the fare is to be deposited by the passenger on entering the car said receptacle having transparent portions through which the coin or fare may be seen after being deposited in the fare box.

A further object is to provide a door or gate to hold the fare in view when desired and permit the fare to descend into a chute when the door is lowered.

A further object is to provide means for depositing the fare into a receptacle, an individual receptacle being provided for each size of coin used as a fare and a further object is to provide means for registering the number of each class of fares used.

Other objects and advantages will be hereinafter set forth and pointed out in the accompanying specification.

Referring to the accompanying drawings which are made a part of this application, Figure 1 is an elevation of the device showing the casing thereof in section. Fig. 2 is a vertical sectional view as seen on line 2—2 Fig. 1. Fig. 3 is a sectional view as seen on line 3—3 Fig. 1. Fig. 4 is a sectional view as seen on line 4—4 Fig. 1.

Referring to the drawings in which similar reference numerals designate corresponding parts throughout the several views, 1 indicates a housing, which may be made of sheet metal or other suitable material, the upper end of the housing having a hopper 2 placed thereon, the walls 3 of which are made of glass or other suitable transparent substance so that the fare may be readily seen after being deposited in the hopper.

In order to prevent the fare descending into the casing or housing until it has been

viewed by the conductor, a gate or door 4 is placed at the lower end of the hopper upon which the coin rests after being deposited into the hopper, said door being hinged at one edge so that it can be readily tilted to deposit the coin or fare into the housing.

The door 4 is normally held in its closed position by means of a spring 5, one end of which is attached to a part of the housing while the other end projects below the door 65 and directs upward pressure against the door, a handle or lever 6 being provided with which to readily lower the door.

After the fare is released from the hopper it descends into a cylindrical chute 7, 70 the interior diameter of which is equal to the diameter of the largest coin used as a fare, said chute terminating above a horizontally disposed circular plate 8 and between the lower end of the chute and said 75 plate is a horizontally disposed rotatable bevel gear 9, the lower face of which is preferably hollowed out to receive said plate, and thus providing a bearing for the gear to revolve upon.

The gear 9 is provided with circular openings 10 into which the fares descend from the chute and as, in this case, but five and ten cent pieces are used, the openings are of large enough diameter to receive the five 85 cent pieces, while the thickness of the gear at the apertured portion is equal to the thickness of a ten cent piece so that but one coin can nest in each opening at a time and in case it is a ten cent piece, the upper face 90 thereof rests flush with the upper face of the gear 9.

The centers of the openings 10 are concentric with the center of rotation of the gear 9 and are adapted to register successively with the chute 7 to allow the coins to nest in the successive openings.

As the five cent piece is thicker than the ten cent piece, the lower end of the chute 7 is slightly raised above the gear 9, or is so positioned that when a five cent piece descends into one of the openings 10, the upper face thereof will just clear the lower end of the chute and as the thickness of two ten cent pieces is greater than the thickness of a five cent piece, but one coin of either denomination will escape from the chute at a time.

The plate 8 is provided with circular apertures 10^a corresponding in diameter to 110

the respective coins to be segregated and extending downwardly from the plate 8 are guides 11 and 12, the guide 11 being arranged under the larger aperture 10^a in plate 8 to receive the five cent fares and the guide 12 being arranged under the smaller aperture 10^a to receive the ten cent fares, and by placing the dime aperture, which occurs above the guide 12 in such position as to encounter the coins first, none but the ten cent fares will enter the same as the opening therein is of such dimension as to admit the ten cent pieces while the five cent pieces will pass thereover and enter the guide 11.

15 The gear 9 is operated through the medium of a gear 13, carried by a shaft 14 extending horizontally through the housing 1, one end of the shaft extending through the housing and having a crank 15 thereon, 20 by which means the shaft may be readily rotated and to prevent reverse rotation of the gear 9, suitable ratchet mechanism 16 is provided on the shaft 14 and the housing 1.

Immediately below the lower ends of the 25 guides 11 and 12, is a drum 17, which is mounted upon a horizontal shaft 18, the periphery of said drum having a plurality of longitudinally extending radial slots 19 and 20 which move into alignment successively 30 with the discharge ends of the guides 11 and 12 respectively, said slots being arranged to receive the coins of different denominations as they descend from the guides, the openings in the guides being so 35 arranged as to deliver the coins edgewise to the slots.

Extending circumferentially of the drum 17 and intersecting the series of slots 19 and 20, are annular grooves 21 and 22, respectively, into which extend the ends of 40 Lell crank levers 23, which are employed, in connection with other connections 24, 25 and 26, to operate any suitable form of registers 27, so as to keep an accurate account of the number of fares of different 45 denominations placed in the fare box.

The drum 17 is rotated by placing a ratchet 28 on the shaft 18, with which cooperates a pawl 29, carried upon an arm 30 also mounted on the shaft 18, a spring 31 being employed to keep the pawl in engagement with the notches in the ratchet. The arm 30 is pivotally mounted on the shaft 18 and is pivotally secured to a shaft 32, extending downwardly from an eccentric 33, carried by the shaft 14, so that as the shaft 14 rotates, the arm 30 will swing downwardly a sufficient distance to give the drum substantially a quarter turn, then upwardly 50 until the pawl engages the next succeeding notch in the ratchet, when the arm will again descend and further rotate the drum.

The drum is held against reverse rotation by providing a suitable ratchet mechanism between the shaft 18 and the wall of

the housing 1, as shown at 34. Located below the drum 17 is any suitable form of receptacle or drawer 35, to receive the coins as they are discharged from the slots in the drum, a guide plate 36 being so located as 70 to direct the coins into the receptacle.

In operation, the fare is deposited in the hopper 2 and descends onto the door 4, when the door is swung downwardly and the coin is deposited into the chute 7. The coins are 75 then in position to enter the openings 10 in the gear 9 and by rotating the gear 9, the coins will be removed from the chute 7, one at a time and deposited in their respective guides 11 or 12, depending on the size of the 80 coin. As the coins descend into the slots in the drum and the drum is rotated, the coins will engage the levers 23 and operate the registers 27, thus keeping accurate count of the number of coins entering the fare 85 box and by providing the ratchets 16 and 34, it will be impossible to reverse the rotation of the parts so as to cause the ten cent pieces to enter the slots intended for the five cent pieces and preventing any 90 possibility of manipulating the machine to defraud the company.

It will be also understood that the parts may be arranged to accommodate coins of different denominations than those specified and it will likewise be understood that this device can be attached to any suitable part of the car and may be used for other purposes than that set forth.

What I claim is:

1. A fare box comprising a cylindrical chute adapted to hold coins in a superimposed relation, a horizontal rotatable plate of the thickness of the thinnest coin to be handled, arranged below and in close relation to said chute the lower surface of said plate being spaced from the bottom of the chute a distance equal to the thickness of the thickest coin to be handled, said plate being provided with a circular aperture 1 of the same diameter as the chute adapted to register with said chute and a plate having segregating apertures therein arranged below said rotatable plate.

2. In a fare box, a coin segregating plate 1 provided with differentiating apertures, a chute arranged below each aperture, said chutes operating to turn the coins from a horizontal to a vertical position, a drum adapted to rotate about a horizontal axis 1 arranged below said chutes and provided with radial slots adapted to receive the coins from said chutes, a registering mechanism, and means operative by the rotation of the drum during the presence of a coin 1 in one of said slots to operate the registering mechanism.

3. In a fare box, a segregating plate provided with differentiating apertures, chutes arranged below said apertures adapted to 1

turn the coins from a horizontal to a vertical position, the longitudinal sides of the bottom of said chutes lying in the same vertical plane, a drum adapted to rotate about a horizontal axis arranged below said chutes, the axis of the drum lying in said vertical plane, said drum being provided with a plurality of radial slots adapted to register with said chutes and receive the respective coins therefrom, and with annular grooves intersecting said slots; a lever disposed in each groove arranged to be actuated by the rotation of the drum during the presence of a coin in one of said slots and a registering mechanism operatively connected to said lever.

4. In a fare box, a coin segregating mechanism, chutes for conducting the separate

coins from the segregating mechanism, the longitudinal edges of the bottom of said chutes lying in the same vertical plane, a drum mounted on a horizontal shaft arranged below said chutes, said shaft lying in said vertical plane, a plurality of radial slots in said drum, adapted to register with the respective chutes, and means for giving said drum a step by step motion whereby the slots are successively halted in alignment with said chutes.

In testimony whereof I have signed my name to this specification in the presence of two subscribing witnesses.

CLYDE C. VOGLESONG.
